UNITED STATES PATENT OFFICE.

HILDING A. SJODAHL, OF CINCINNATI, OHIO.

DESIGN FOR A SHINGLE STRIP.

Application filed December 7, 1925. Serial No. 15,668. Term of patent 14 years.

To all whom it may concern:

Be it known that I, HILDING A. SJODAHL, a citizen of the United States, residing in the city of Cincinnati, county of Hamilton, and State of Ohio, have invented a new, original, and ornamental Design for a Shingle Strip, of which the following is a specification, reference being had to the accompanying drawing, forming part thereof.

In the drawing:

The figure represents a plan view of a shingle strip showing my new design.

I claim:

The ornamental design for a shingle strip as shown.

HILDING A. SJODAHL.
